DESIGN FOR A BOWLING BALL SUPPORT

Edward G. Roberts, Oak Park, Ill.

Application May 7, 1941, Serial No. 100,832

Term of patent 14 years

To all whom it may concern:

Be it known that I, Edward G. Roberts, a citizen of the United States of America, residing at Oak Park, Cook County, Illinois, have invented a new, original, and ornamental Design for a Bowling Ball Support, of which the following is a specification, reference being had to the accompanying drawing forming a part thereof.

Figure 1 is a top plan view of a bowling ball support, showing my new design.

Fig. 2 is a sectional view of Fig. 1 taken in the direction of the arrows along the line 2—2 therein.

I claim:

The ornamental design for a bowling ball support, as shown.

EDWARD G. ROBERTS.
